VALVE CONSTRUCTION FOR WASHING APPARATUS

Edgar S. Stoddard, Berwyn, Ill., assignor to Edison General Electric Appliance Company, Inc., Chicago, Ill., a corporation of New York

Application February 27, 1941, Serial No. 380,853

7 Claims. (CL 137—139)

This invention relates to a valve construction for a washing apparatus and more particularly to a drain valve construction for a dishwashing apparatus and has for its object the provision of an improved valve construction which is reliable in operation and relatively inexpensive to manufacture.

While not limited thereto, this invention relates to a new and improved electromagnetically operated valve especially adapted for use as a drain valve of a dishwashing apparatus and it is among the objects of this invention to provide an improved valve of this character.

As is well known in the dishwashing art, the waste fluid which the drain valve is called upon to handle often contains a rather high concentration of greases and other sticky substances. It has been found in the past that these substances often accumulated around the valve seat of the drain valve, causing the valve either to fail to seat properly or to stick in its closed position. It is among the objects of this invention to provide an improved drain valve construction in which such operational failures are eliminated. In this regard it is a specific object of this invention to provide an improved drain valve construction for a dishwasher in which, prior to opening, the valve element is given a hammer blow to completely disengage it from the valve seat.

It is among the further objects of this invention to provide new and improved means for electromagnetically operating the improved valve construction referred to above so that it will be quickly and relatively silently actuated upon the energization of the electromagnetic means and to provide improved means for connecting the electromagnetic means to the valve means so that the proper adjustment may be attained to insure maximum pull on the valve by the magnetic means.

It is a further object of this invention to provide improved means for venting the valve construction so that failure of the valve to open due to the building up of a back pressure on the discharge side thereof is prevented.

Further and more specific objects of this invention will become apparent as the following description proceeds and the features of novelty which characterize this invention will be set forth in the claims appended to and forming a part of this specification.

For a more complete understanding of this invention reference should be had to the accom-

panying drawings in which Fig. 1 is a front elevation of a dishwashing apparatus embodying the drain valve construction of this invention; Fig. 2 is an enlarged front elevation showing in detail the improved valve construction of this invention; Fig. 3 is a top view of the valve construction shown in Fig. 2; Fig. 4 is a sectional view taken on the line 4—4 of Fig. 3, and looking in direction of arrows showing further details of the valve construction; Fig. 5 is a sectional view taken on the line 5—5 of Fig. 2, and looking in direction of arrows showing additional details of the valve construction; and Fig. 6 is an enlarged sectional view taken on the line 6—6 of Fig. 1, and looking in direction of arrows showing the outlet construction for the improved valve venting arrangement of this invention.

Referring to the drawings this invention has been shown as applied to a dishwashing apparatus of the front opening type which comprises a vat 10 suitably supported in a casing having side walls 11 and 12, a rear wall 13, and a top wall 14. Provided in the top wall is an integrally formed back splasher plate 15 in which is mounted suitably manually operable control means 16 for controlling the various electrically operated element of the dishwashing apparatus. Arranged to close the front opening of the vat 10 is a door 17 in which is provided a ventilating louver 18 and in the upper left-hand corner of which is provided suitable detergent supplying means 19.

As shown in Fig. 1, the bottom wall 20 of the vat 10 slopes downwardly so as to define a receptacle 21 for receiving a washing fluid. Provided within the receptacle 21 is an impeller 22 which is adapted to be driven by a suitable motor 23 positioned outside of and below the bottom wall 20, as illustrated. When driven by the motor 23 the impeller picks up the washing fluid in the receptacle 21 and throws or hurls the fluid up through the washing vat 10 into contact with dishes contained therein. It will be understood that suitable rack means (not shown) will be used for supporting the dishes within the vat 10.

The motor 23 is supported by means of suitable brackets 24 which are secured to a drain casting 25 mounted on the bottom wall 20 of the vat in the manner more fully described and claimed in my copending application Serial No. 380,849 filed Feb. 27, 1941, and assigned to the assignee of the present invention.

Washing fluid which is preferably warm water is supplied to the vat 10 by means of a suitable

spray device 26 which is supported in the central portion of the top wall of the vat, as shown in Fig. 1. This spray device is connected by means of suitable pipe 27 which extends downwardly along the outside of the vat between the vat and the rear wall 13 of the casing to the outlet side of a control valve 28, the inlet side of which is connected by piping 29 to a suitable source of supply of washing fluid. The valve 28 controls the quantity of washing fluid supplied to the vat and in the preferred form of this invention it is electromagnetically operated by means of a suitable solenoid 30 which is energized in accordance with the positioning of the control means 16. It will be observed that the valve 28 is located behind the motor 23 and its supported in position by means of a bracket 31 as more particularly described in my aforementioned copending application.

Waste fluid is drained from the receptacle 21 through the drain casting 25 and into a drain elbow 32 from which it is discharged into a suitable trap connection 33 which is connected to a drain system (not shown).

As previously pointed out, this invention relates to the provision of new and improved means for controlling the flow of waste fluid from the washing vat so that washing fluid may be accumulated in the vat for a portion of a washing cycle and may thereafter be quickly and reliably discharged from the washing vat into the drain system.

The improved drain valve construction for effecting this controlling function is shown in detail in Figs. 2 through 5. Referring to these figures and particularly Figs. 4 and 5, it will be observed that the improved drain valve construction includes a drain elbow 32 which is mounted on a drain casting 25. Secured between the discharge opening of the drain casting and the inlet opening of the drain elbow is a valve seat casting 34 which includes a flange 35 which is adapted to fit over the flange 36 provided at the discharge opening of the drain casting and a flange 37 which is adapted to be received within the flange 38 provided at the inlet opening of the drain elbow. Positioned between the flanges 35-36 and 37-38 are the gaskets 39 and 40 respectively for providing a fluid-tight seal. Provided for securing the drain elbow and valve seat to the drain casting is a pair of bolts 41 which are threadedly received in the drain casting and when drawn down tight, firmly hold the elements in fluid-tight relation.

The flanges 35 and 37 are spaced apart by means of the tubular portion 42. Projecting outwardly from the flange 37 is a discharge portion 43 which is adapted to extend into the drain elbow, as shown in Fig. 4, to form a valve seat 44 for the valve element or flapper 45. This valve element is of the swing check valve type and it is swingably or pivotally supported by means of the arm 46 which is supported on a pin 47 rotatably journaled in a pair of arms 48 integrally formed on the valve seat casting 34. It will thus be observed that the valve seat casting and the valve element constitute a unitary assembly which can readily be mounted in position on the drain casting with the valve portion projecting into the drain elbow. The bolt openings in the pairs of flanges 35-36 and 37-38 are positioned so that flapper 45 is held in a vertical position. When in this position the flapper 45 will rest against the valve seat

44 due to the pitch of the seat which is approximately 15°. However, the flapper is free to swing open to permit the free discharge of fluid into the drain elbow. However, in the event that fluid should back up into the drain elbow from the waste system due to the fact that the drain elbow lies below the discharge point of other devices connected to the drain system, for example, a sink outlet, the valve element 45 is free to swing to the closed position and prevent such waste fluids from backing up into the washing apparatus.

In order to move the drain valve from its normally free swinging drain open position to a positively held closed position there is provided within the drain elbow an arm 49 which normally lies out of engagement with the flapper element 45. As shown in dotted lines in Fig. 4, however, the arm 49 is adapted to be moved into engagement with an abutment 50 provided on the flapper to hold the flapper firmly against the valve seat 44 to produce a closed position for the valve. The arm 49 is secured by means of the set screw 51 to a shaft 52 which is journaled in the side walls of the drain elbow and has one end projecting through one side wall of the elbow. A suitable packing gland 53 is provided to insure that no fluid will leak outwardly along the shaft at the point where it extends through the elbow. Secured to the projecting end of the shaft 52 by means of a set screw 54 is a T-shaped lever 55. By moving this lever clockwise as viewed in Figs. 1 and 2, the arm 49 will be rotated from the full line position to the dotted line position in which position it engages the abutment 50 to hold the valve in the closed position. In order to bias the arm 49 to its normal position shown in full lines in Fig. 4 in which it does not obstruct the free swinging movement of the flapper 45 there is provided a torsion spring 56 which is wound on a sleeve 57 mounted on the projecting end of shaft 52. The spring 56 has one end secured in an opening provided in the head portion of the T-shaped lever 55 and has its opposite end secured in a suitable eyelet provided in the bracket 58 formed on the drain elbow. The sleeve 57 is mounted on the shaft so as to be supported between two spaced washers 59 and is held in position by means of a cotter pin 60.

In accordance with this invention the movement of the drain valve from its normally open to its closed position and from its closed position to its normally open position is electromagnetically controlled. In other words, electromagnetic means are provided for actuating the arm 49 and the energization of the electromagnetic means is controlled in accordance with the movement of the control switch 16. The details of construction of the improved electromagnetic means are best illustrated in Figs. 2 and 3 and referring to these figures it will be observed that there is cast on the drain elbow a suitable supporting flange 61 to which a coil supporting bracket 62 is adjustably secured by suitable means such as screws 63 adjustable in the slots 64 provided in the bracket. This coil supporting bracket is substantially rectangular in shape and is provided with a central opening in which an electromagnet is resiliently supported by means of a plurality of tension springs 65. The electromagnet comprises a laminated core 66 upon which is wound a coil 67 and within which moves a laminated armature 68 comprising a plurality of strips secured together in a

stack. The two outside strips of this laminated core extend beyond the ends of the remaining strips so as to form a U-shaped frame in which is secured a pin 69 upon which is provided a pair of spacers 70.

In order to transmit the movement of the armature 68 to the outer lever 55 a tension spring 71 is provided between the pin 69 and an ear 72 provided on the head portion of the T-shaped lever 55. Such a construction is preferred over the use of a solid connection between the armature and the lever since the tension spring increases the travel of the armature over that obtained with a fixed connector. Moreover, with the tension spring transmitting arrangement the accuracy with which the armature must be positioned relative to the lever 55 in order to effectively close the flapper 45 is not as great. With a fixed connector between the two operative elements a poor adjustment results in unsatisfactory operation of the electromagnetic means. For example, if the adjustment is such that the armature cannot go all the way into the coil to provide a magnetic seal, the coil will vibrate. On the other hand if the adjustment is such that the armature reaches the limit of its travel too quickly the valve will not be held tightly closed. By employing a resilient connector between the operative elements, these difficulties in adjusting the elements relative to each other are substantially overcome and in addition the noise encountered in operating the electromagnetic means and the valve is substantially decreased.

In Figs. 2 and 3 the electromagnetic operating means is shown in its normally deenergized position. When in this position the valve operating arm 49 is in the full line position shown in Fig. 4 and the flapper 45 is in its normally free swinging position. When the coil 67 is energized, the armature 68 is retracted and the lever 55 is moved clockwise as viewed in Figs. 1 and 2. This causes the arm 49 to be moved clockwise as viewed in Fig. 4 to the dotted line position shown in this figure, in which position the flapper 45 is firmly held against the valve seat 44 to prevent the discharge of fluid from the washing apparatus. It will be understood that the adjoining surfaces of the flapper 45 and of the valve seat 44 are interfitting as by grinding or the like so as to provide a fluid-tight relation between the two when the flapper is tightly held against the seat.

When the coil 67 is deenergized, the armature 68 is pulled outwardly to the position shown in Figs. 2 and 3 under the influence of the tension of springs 71 and 56 and at the same time the arm 49 is rotated counterclockwise to the full line position shown in Fig. 4, permitting the valve to return to its normally free swinging position.

It has been found that when the waste waters which are discharged through the drain valve are sticky in character there is a tendency for the flapper 45 to stick closed. This of course has certain detrimental effects on the washing apparatus and interferes with the remainder of the washing positions of the control 16. In order to eliminate the possibility of the flapper sticking under such conditions there is provided in accordance with this invention means for imparting a hammer blow to the valve at the time the arm 49 is permitted to return to its normal position. This means includes a hook-shaped abutment 73 which is integrally formed on the valve arm 46 and extends above and outwardly to the right from the pivot pin 47, as shown in Fig. 4.

To accommodate the arm 73, the drain elbow is provided with a rectangular-shaped well 74 at the top thereof. Integrally formed on the arm 49 is an upwardly projecting arm 75 which normally lies within the hook-shaped abutment 73. However, upon movement of the arm 49 in a clockwise direction so as to move the valve to its closed position, the arm 75 will move clockwise past the end of the arm 73 to the dotted position shown in Fig. 4. Thus when the coil 67 is deenergized and the arm 49 is moved counterclockwise under the influence of the biasing spring 56, the end of the arm 75 will strike against the outside edge of the arm 73 imparting a hammer blow to the flapper 45 which positively breaks it away from the seat 44. After imparting such a hammer blow the arm 75 continues to move in a counterclockwise direction to its normal position within the hook portion of arm 73, as shown in full lines in Fig. 4. It will thus be observed that there is provided in accordance with this invention relatively simple, yet highly effective means for preventing the flapper 45 from becoming stuck to the valve seat 44 at any time during its operation.

It has also been found that the formation of air pockets in the drain elbow, on the discharge side of the valve, may affect the operation of the valve, by interfering with the free swinging of the flapper element 45. In order to eliminate the possibility of such an air pocket forming in the drain elbow, a vent opening 76 is provided near the top of the well 74. Without such a vent it is possible for air to be pocketed between the inlet side of the valve and the water standing in the trap 33 so that the valve will be held shut against a slight head of water in the tub. The reason that this occurs is that it is difficult for the air in the upper portion of the drain elbow to travel horizontally through the valve and up into the tub. By relieving the pressure through the vent opening the free swinging of the flapper 45 is unimpeded.

In order to permit the valve to function properly, only a small vent opening is required in the top of the drain elbow. Even such a vent, however, would be likely to permit water to spill on the floor through the vent if the drain did not operate rapidly. For this reason a tube 77 is attached to the opening by means of the bushing 78 to carry the vent above the normal water level in the tub. When the washing apparatus is connected to the same drain system as an adjoining sink it is necessary to carry the vent tube at least as high as the entrance to the sink drain in order to avoid water that might be accumulated in the sink drain from backing up through the vent. Moreover, provision must also be made to prevent the pumping of water out of the vent and onto the floor due to pressures produced on the drain side of the valve by other apparatus connected to the drain system. For these reasons the vent tube is projected upwardly between the back of the vat and the rear wall 13 of the casing and is brought into the vat below the top wall thereof. In this position the vent is sufficiently high for most normal installations of the dishwasher and any water that is pumped or forced out through the vent is returned to the interior of the vat.

As shown in Fig. 6, the connection of the vent tube to the vat is effected by means of a bushing 79 into which the upper end of the tube 77 projects. This bushing is firmly secured to the rear wall of the vat 16 by means of a nut 80 and

the point at which it passes through the wall of the vat is sealed by means of gaskets 81. In order to limit the amount of water that might be pumped into the vat through the vent opening in a short space of time, the discharge end of the bushing is provided with a small opening 82. Of course, the same effect could be obtained by making the vent tube 77 of smaller diameter. However, it has been found that this is not satisfactory since the vent tube would tend to clog, especially if food pulp from the waste unit were forced into the tube.

It is believed that the operation of the improved drain valve construction of this invention is clear from the foregoing detailed description. It is to be observed that there is provided in accordance with this invention an improved valve construction particularly adapted for use as the drain valve of a dishwashing apparatus. Moreover, it will be observed that there is provided a drain valve which is relatively simple in construction and may be easily mounted in its operative position in a dishwashing apparatus. Furthermore, it will be observed that there is provided an improved drain valve construction which is thoroughly reliable in operation in that means are provided for preventing the valve from either sticking or being held in its closed position after the electromagnetic operating means have been actuated to cause it to be moved to its normally open position.

While there is shown a particular embodiment of this invention it will be understood of course that it is not desired to be limited thereto since many modifications may be made thereof and it is therefore contemplated by the appended claims to cover any such modifications as fall within the true spirit and scope of this invention.

What I claim as new and desire to secure by Letters Patent of the United States is:

1. A valve construction comprising a body member, a separable valve seat projecting into said body member, a valve member pivotally mounted on said valve seat so as to cooperate with said seat and lie within said body member, said valve member being mounted so that normally it swings freely about its pivot, a valve operating arm within said body member, means for actuating said arm in one direction to bring it into engagement with said valve element to move said element from its normally free swinging position to a closed position in engagement with said valve seat, means for biasing said arm in the opposite direction so as to move it out of engagement with said valve element and permit said valve element to return to its normal free swinging position, and means on said arm for imparting a sharp blow to said element in the initial portion of the movement of said arm in said opposite direction so that any tendency of said valve element to stick closed is prevented.

2. A valve construction comprising an elbow, a valve seat projecting into said elbow, a valve element pivotally mounted within said elbow so as to cooperate with said valve seat, said valve element having a normally free swinging position in which it is out of engagement with said valve seat, an operating arm rotatably mounted in said elbow, a projecting portion on said arm adapted to be moved into engagement with said valve element to move it from said normally free swinging position to a closed position in engagement with said valve seat, means outside of said elbow for rotating said arm so that said portion engages said valve element and holds said element against said seat, and means on said arm for imparting a sharp blow to said element in the initial portion of the movement of said arm in said opposite direction so that any tendency of said valve element to stick closed is prevented.

3. A valve construction for a dishwashing apparatus having a drain casting comprising a drain elbow, a valve seat casting having a portion adapted to project into said drain elbow, means for mounting said valve seat casting between said drain elbow and said drain casting, so that said portion projects into said elbow, a valve seat on said projecting portion of said valve seat casting, a valve element adapted to cooperate with said valve seat, means for pivotally mounting said valve element on said projecting portion of said valve seat casting, said means permitting normal free swinging movement of said valve element out of engagement with said valve seat, a projecting arm on said valve element, an actuating arm pivotally mounted within said drain elbow, means on said actuating arm adapted to engage said valve element to move it from its normal free swinging position to a closed position in engagement with said valve seat, and additional means on said actuating arm adapted to engage said arm on said valve element to impart a sharp blow to said arm upon movement of said actuating arm out of engagement with said valve element so as to prevent said valve element from becoming stuck in said closed position.

4. A valve construction comprising an elbow, a valve seat projecting into said elbow, a valve element pivotally mounted to cooperate with said valve seat, said valve element having a normally free swinging position in which it is out of engagement with said valve seat, an operating arm rotatably mounted in said elbow, a projecting portion on said arm adapted to be moved into engagement with said valve element to move it from said normal free swinging position to a closed position in engagement with said valve seat, means outside of said elbow for rotating said arm so that said portion engages said valve element and holds said element against said seat, means for biasing said operating arm out of engagement with said valve element so as to permit said valve element to return to its normal free swinging position when the holding effect of said portion of said arm is removed, a second portion on said arm adapted to engage said valve element to impart a sharp blow thereto so as to free said element from said valve seat in the event that it is stuck thereto, and vent means in said elbow for venting the discharge side of said valve element so that interference with the free swinging operation of said valve element in said drain elbow by air trapped on the discharge side of said element is prevented.

5. A valve construction comprising a body member, a valve seat projecting into said body member, a valve element pivotally mounted to cooperate with said valve seat, said valve element having a normal free swinging position in which it is out of engagement with said valve seat, an operating lever rotatably mounted in said body member having a portion adapted to be moved into engagement with said valve element to move it from its normal free swinging position to a

closed position in which said element is brought into engagement with said valve seat, means for biasing said operating lever so that said portion is out of engagement with said valve element and permits said normal free swinging movement of said element, a second portion on said operating lever adapted to engage a portion of said valve element to impart a sharp blow thereto upon movement of said operating lever under the influence of said biasing means, a vent opening in said body member for venting the discharge side of said valve element to prevent trapped air on the discharge side of said element from interfering with the normal free swinging operation of said valve element, and an open-ended tube connected to said vent opening for raising the effective level of said vent opening.

6. A valve construction comprising a body member, a removable valve seat projecting into said body member, a valve element adapted to engage said valve seat to produce a closed position for said valve construction, means for pivotally mounting said valve element within said body so that said valve element can normally freely swing out of or into engagement with said valve seat depending upon the direction of the fluid pressure applied to said element, and a vent in said valve body on the discharge side of said valve seat for preventing air trapped on said discharge side of said valve element from interfering with the free swinging operation of said element.

7. A drain valve construction for a dishwashing vat comprising a drain elbow, a valve seat

casting having a portion projecting into said drain elbow, means for securing said drain elbow and said casting to said vat so that said portion lies within said elbow, a valve seat on said portion lying within said elbow, a valve element adapted to cooperate with said valve seat, means for pivotally mounting said valve element on said portion of said valve seat casting lying within said elbow so that said element freely swings into and out of engagement with said valve seat in accordance with the fluid pressure exerted on said element, an operating arm rotatably mounted within said drain elbow having a portion adapted to be moved into engagement with said valve element to positively move said element to a closed position against said valve seat and hold said element in said closed position, means for biasing said operating arm out of engagement with said valve element so as not to interfere with said free swinging movement of said element, electromagnetic means supported outside of said drain elbow for operating said arm and holding it in engagement with said valve element against the force of said biasing means, a vent in said drain elbow on the discharge side of said valve element for preventing any air trapped on said discharge side of said valve element from interfering with the free swinging operation of said element, and a vent tube secured to said vent opening and adapted to extend into said dishwashing vat for carrying into said vat any fluids discharged through said vent opening.

EDGAR S. STODDARD.
